CLAIM

The ornamental design for faucet, as shown and described.

DESCRIPTION

FIG. 1 is an oblique side view of a faucet showing our new design;

FIG. 2 is an opposite-side oblique side view thereof;

FIG. 3 is a front elevational view thereof;

FIG. 4 is a side elevational view with the opposite side a mirror image thereof;

FIG. 5 is bottom view thereof; and,

FIG. 6 is a top view thereof.

The broken lines shown in the faucet spout and on the back of the faucet are included for the purpose of illustrating a portion of the faucet that forms no part of the claimed design.
